CLAIM

The ornamental design for a swirl-shaped container, as shown and described.

DESCRIPTION

FIG. 1 is a front perspective view of a swirl-shaped container, showing my new design;

FIG. 2 is an exploded front perspective view thereof;

FIG. 3 is an exploded front elevational view thereof, the rear elevational view being a mirror image thereof;

FIG. 4 is an exploded left-side elevational view thereof, the right-side elevational view being a mirror image thereof;

FIG. 5 is an exploded top plan view thereof;

FIG. 6 is an exploded bottom plan view thereof; and,

FIG. 7 is an exploded cross-sectional view thereof, taken along line 7--7 of FIG. 5.

The broken lines in the figures depict portions of the swirl-shaped container that form no part of the claimed design.

1 Claim, 7 Drawing Sheets
